INVENTOR.

John Dopyera

134 *Father L. Macay*
Attorney.

UNITED STATES PATENT OFFICE.

JOHN DOPYERA, OF LOS ANGELES, CALIFORNIA.

MUSICAL INSTRUMENT.

Application filed August 16, 1924. Serial No. 732,465.

This invention relates generally to musical instruments and more particularly to string instruments such as banjos, mandolins, guitars and the like, and has for a main object the provision of an instrument with an all metal body composed of a plurality of thin metallic members detachably held together, and so arranged as to provide a highly resonant instrument and embodying details of improvements not heretofore used in instruments of this type.

Another object is to provide an instrument having a body composed of a hollow metallic band over which a skin is adapted to be stretched as in the case of a banjo, or to which the sounding board may be suitably attached as in the case of a mandolin and guitar, and provided on the back thereof with a substantially enlarged hollow cover forming a primary resonator by means of which the vibrations set up when the instrument is played will be amplified and louder and more sustained tones provided than is possible in obtaining types of such instruments.

Another object is to provide an auxiliary resonator enclosed by said cover and supported thereon for still further amplifying the sound produced when the instrument is played.

Another object is to provide means whereby the several parts of the instrument may be detachably held together so that the same may be quickly assembled and dis-assembled as hereinafter more particularly described.

I have shown one practical embodiment of my invention in the accompanying drawings, applied to a banjo, in which similar characters of reference are employed throughout the several views for indicating the same and like parts.

In said drawings:

Fig. 1 is a top plan view of the instrument with the neck partially broken away.

Fig. 2 is a side elevation of the same, partly in section.

Fig. 3 is a bottom plan view of the same, with the resonator cover removed.

Fig. 4 is a typical transverse section of the same on line 4-4 of Fig. 1.

Fig. 5 is a transverse section of the same on line 5-5 showing a modified form and arrangement of the cover.

Fig. 6 is a diametrical section of the cover and resonator of slightly modified form from that shown in Fig. 2.

Fig. 7 is a fragmentary transverse section on line 7-7 of Fig. 3; and

Fig. 8 is an interior face view of a suitable mounting for an electric socket such as shown in Figs. 3 and 7 whereby the interior of the instrument may be lighted by electricity during use.

In the consideration of this invention reference is had to my pending application for patent for banjos, filed Dec. 12, 1923; Serial Number 680,145.

Referring now in detail to the drawings of my improved musical instrument, it will be observed that the same embodies as primary parts thereof an annular band or ring B to the top of which the usual skin S is applied and held in position by means of a narrower band b; a cover C on the back of the instrument is adapted to be removably held on the band B and a resonator R which is enclosed by the cover C and is supported thereon as shown in Fig. 2. The arrangement and connections of the members described are more clearly shown in Fig. 4, which I will now describe.

The band B is of thin sheet or cast metal and partakes of the form of a continuous ring of lighter weight metal, such as aluminum. An outer band B' encompasses the band B and has its upper edge portion e inwardly turned and rolled over the upper edge of band B, while the lower edge portion e' is similarly turned inwardly and rolled over the lower edge of said band B. The intermediate portion of band B' is turned outwardly for a substantial distance around the central portion thereof, and thence inwardly where it abuts the outer periphery of band B, thus providing a flange f of double thickness wherewith to provide a support for the cover C.

The skin S is tightly stretched over the curved portion e of the outer band B' as shown in Fig. 4, and extends downwardly over the outer periphery of said band B' and thence outwardly, upwardly and inwardly over the four sides of a rectangular ring r which encompasses the body portion of band B'. The skin retaining band b is also curved at its upper edge and has an annular groove g formed therein which is open on the outer periphery of the band and is so formed that an upwardly extended annular rib 1 is provided at the bottom of the open part of said groove, whereby a plurality of rods 2, may be attached to the band b by

means of hooks *h* formed on the upper ends of said members and adapted to fit in the groove *g* and to overlie the annular rib 1.

The lower ends of the members 2 are threaded at 3 and extended through openings 4 in the flange *f* of the outer band *B'* and are provided below said flange with nuts 5, which are threaded onto the lower ends of said members 2, so that when said nuts 10 are tightened the members 2, will be drawn downwardly and the band *b* will be also drawn downwardly over the outer portion of band *B'*, the band *b* having an annular recess at 6 formed on the inner side thereof 15 and at the bottom for receiving the edge portion of the skin *S* and the ring *r*. Thus, when the band *b* is drawn downwardly by tightening the nuts 5, the ring *r* will also be drawn downwardly and the skin *S* will 20 be tightened over the upper edge *e* of band *B'*.

The cover *C* is integrally formed of sheet or cast metal and rolled or molded into the form shown, and it will be noted that the diameter of the said cover is substantially 25 larger than the diameter of the head of the instrument.

The cover *C* has an annular outer portion 7 of semi-circular cross section with an inwardly turned flange 8 underlying the flange *f* of bands *B'*, and said cover is detachably held on said band *B'* by means of a plurality of screws 9, with the heads thereof underlying the flange 8 of the cover, and the 30 outer ends thereof extended through said flange 8 and the two thicknesses of metal composing the flange *f* of member *B'* and nuts 10, are provided on the upper side of said flange *f*, which are threaded onto the 35 ends of the said screws for holding the cover firmly in position and in concentric relation with the body band *b*.

The cover is provided on its upper side and externally of the flange *f* with a plurality of openings *O*, whereby the tones produced by the playing of the instrument may be emitted in substantial volume. The outer portion 7 of said cover continues inwardly forming a back portion *a* which is flared outwardly for a substantial distance as shown in 45 Fig. 2, and said portion *a* is substantially spaced from the portions *e'* of the band *B'*, so that the cover is held in contact with the band *B'* only at points near the outer periphery of the flange *f*, so that the vibrations 50 set up by the playing of the instrument may be amplified to a maximum extent and the tones will not be impaired by contact with other parts of the instrument.

60 The resonator *R* is also formed of thin metal and may be adjustably held on the cover *C*, as shown in Fig. 2, or fixed thereto at the edge, as shown in Fig. 6, as occasion may warrant. In some cases and on some 65 instruments, depending upon the size and

character of the individual instrument, and upon the quality of the tones desired, it may be desirable to modify the structure shown to meet desired conditions.

In the form of device shown in Fig. 2 the back portion *a* of the cover *C* is provided in the center of the instrument with a concave portion 11, and the resonator *R* is similarly provided with a concave portion 12 in the center thereof so as to provide means 70 for adjustably connecting the resonator *R* with the portion *a* of cover *C*. This connection is accomplished by means of a stud 13 which is threaded into the portion 12 of the resonator which is reinforced by means 75 of the washer 14 soldered or otherwise attached thereto for providing additional threads, and the outer end of said stud is extended through the portion 11 of the cover and is reversely threaded into a detachable 80 head 15 carried on the outer end of said stud, whereby the stud may be turned for moving the resonator relative to the back of the cover *C*. A spring 16 is carried on the stud 13 between the portion 11 of cover *C* and the portion 12 of resonator *R* which exerts tension 85 on the resonator for preventing the turning thereof when the stud is turned.

The outer edge 17 of the resonator is 90 annularly formed and is adapted to rest against the flat portion *a'* on the back of cover *C*, or as occasion may arise, when the stud 13 is turned the edge 17 may be adjusted so as to be spaced from the portion *a'* of the cover. The vibrations produced in 95 the playing of the instrument are modified to a greater or less extent by reason of the engagement or dis-engagement of the annular edge 17 of the resonator with the portion 17' of the cover.

100 However, as hereinbefore stated, it may be desirable in some cases to dispense with the adjustable connection between the cover *C* and resonator *R*, and in such case, as shown in Fig. 6, the portions 11 and 12 of 105 the cover and resonator respectively, are omitted and the annular portion 17 of the resonator may be soldered or otherwise attached permanently to the portion *a'* of the cover *C* at points 18, as shown.

The neck *N* of the instrument is attached to the bands *B* and *B'* so as to be capable of removal therefrom as shown in Fig. 3. For this purpose a metallic rod 20 is extended diametrically across the interior of the instrument at a point about midway of the portions *e* and *e'*, and one end thereof is attached to said bands by means of a screw 21 having its head on the outer side of band *B'*, and having its threaded stem screwed into the end 22 of said rod, one or more washers 23 being provided between the end of the rod and the band *B* as shown in Fig. 3.

115 The other end of rod 20 is adapted to be attached to the neck *N* by means of a screw 120

24 which has a square or hexagonal head 25 adapted to seat in and to be non-rotatively held in a correspondingly formed recess 26 formed in the neck N, while the stem of the 5 screw extends through an elongated bore 27 in the neck and through corresponding openings in the bands B and B', and is adapted to be threaded into the adjacent ends of rod 20, the washers 23 being also placed at 10 the end of the rod 20 adjacent the inner band B. Thus, when the rod 20 is threaded tightly onto the inner end of screw 24 the screw 21 in the other end of said rod may be threaded into said end of the rod and the 15 neck N will be drawn tightly against the outer periphery of band B' and will be firmly and substantially held in position for holding the instrument during use.

The tail piece T is applied to the outer 20 side of the band B' as in the case of other instruments and at a point on the diametric line of the neck N so that the upper portion of said tail piece will overlie the skin S and strings W, W', W¹ and W² are suitably attached to said tail piece and are held in spaced relation with respect to the skin S, by means of the usual bridge d. The strings are adapted to be stretched to the proper tension by means of the usual keys (not shown) 30 mounted on the outer end of the neck N.

Referring to Fig. 5, I may find it convenient and desirable to form the cover C of two pieces of thin metal instead of one, as shown in Fig. 4, so that the same may be more 35 readily rolled into desired form. In this case the upper part of the cover will be provided with the portion a underlying the flange f of band B' as in the other form, but the outer portion of said band is preferably turned upwardly around the outer edge of flange f to a point flush with said upper edge, and thence rolled outwardly and downwardly where the lower edge thereof may be connected with the lower part of the cover 40 by means of an interlocking bead 30, and the lower part continues thence downwardly and inwardly where it will join the portions a' and a for forming the continuous closed 45 cover shown in the other form of device.

50 It is desirable in many cases in the provision of an instrument of this kind to provide means for lighting the interior of the instrument, especially during performances, and to this end the internal rod 20 which reinforces the interior of the instrument and also serves to support the neck N affords opportunity for conveniently mounting a pair or more of electric lights, as at L and L' within the instrument. Said lights are attached to sockets 31, and 31' respectively, which are carried on bars 32 and 32' attached at their inner ends to arms 33 and 33' formed on a central sleeve 34 which is clamped on the rod 20 by means of a screw 55 35. Members d and 32' are attached re-

spectively to the arms 33 and 33' by means of screws 36 and 36' and the sleeve 34 is insulated from the rod 20 by means of a bushing 37 of insulating material.

The bands B and B' are provided with 70 openings 38 therein at a point near the tail piece T by means of which connection may be made between the lamps L and L' with a source of electric current supply. This connection includes a socket 39 which is 75 carried in a clamp device 40 formed of sheet metal and having a socket receiving portion 41 adapted to be clamped tightly around the socket at the ends 42 thereof by means of a screw 43 and a lower portion 44 adapted to 80 be attached by suitable means to the band B on the interior of the instrument.

A plug 45 is connected in the usual manner to the socket 39 and has wires 46 and 47 adapted to connect with the source of electric 85 current. The socket 39 has two pairs of wires 48 and 49 and 48' and 49' which lead to the lamps L and L' respectively, so that the lamps will be energized for illuminating the interior of the instrument when the plug 90 45 is attached to the socket 39.

Now, it will be understood that in the provision of the instrument herein shown and described, I have provided numerous improvements over obtaining and heretofore 95 known types of instruments, said improvement embodying an instrument having an all metal body formed of thin sheet metal of light weight and substituting, for instance, the light metallic band B for the usual 100 wooden band which is employed in instruments heretofore known and used. Also, by means of the structure shown and described, the lugs as employed for attaching the members 2, to the instrument have been eliminated and altogether a more ornamental and 105 slightly instrument is provided than is possible with the well known types of such instruments.

The metal bands, in addition to being of 110 light weight are susceptible to greater ornamentation than their equivalent in wooden bands, as the same may be plated in gold or silver throughout and otherwise ornamented as may be desired. Furthermore the 115 connections between the several parts of the instrument are such that a novice may readily assemble and disassemble the instrument, and greater tone values are possible with an instrument of this kind than with instruments employing wooden bands of the character heretofore known and used.

It will be understood that I may modify or change my invention within the scope of the appended claims without departing from 120 the spirit thereof.

What I claim is:

1. A stringed musical instrument comprising a ring with a skin stretched thereover, an outer band encompassing and having 130

edge portions bent inwardly over the edges of said ring and an outwardly extending annular flange intermediate said edge portions, a metallic cover over the back of said instrument having a peripheral portion of 5
arcuate cross section of substantially greater diameter than said band and having the edge thereof bent inwardly under the flange of said band, and means for detachably sup- 10
porting said cover on said band.

2. A stringed musical instrument as characterized in claim 1, including a metallic resonator supported on and inwardly of said cover and spaced from said ring and said 15
band.

3. A stringed musical instrument as characterized in claim 1, including a resonator spaced from said ring and said band, and means for resiliently connecting said resonator to said cover. 20

4. A stringed musical instrument as characterized in claim 1, including a resonator, said cover and said resonator having centrally formed cupped portion, an adjusting screw connecting said cupped portions, and a 25
spring on said screw compressed between said cover and said resonator for holding said members in adjusted positions.

JOHN DOPYERA.
